FLASHER BULB

Paul A. Nothstine, Dayton, Ohio

Application August 18, 1928, Serial No. 300,561

5 Claims. (Cl. 176—14)

My invention relates to flashing lamps, and more particularly to an incandescent lamp having incorporated therein as a part of its unitary structure, a thermostatic control member, having operative connection with the lamp filament, whereby an intermittent flashing action is effected.

The present construction is a further development of that shown and described in copending application, Serial No. 206,566 filed July 18, 1927, wherein the thermostatic flasher switch or control element is located interiorly of the bulb in the same compartment with the filament. In the present method of assembly, the tubulation stem of the lamp bulb is utilized as a support for the thermostatic control element within the hollow mount. The present thermostatic control means may be applied to existing lamps as purchased in the open market.

10 The object of the invention is to simplify the structure, as well as the means and mode of operation of automatic flasher lamps, whereby they will not only be cheapened in construction, but will be more efficient in use, positive in operation, uniform in action and unlikely to get out of repair.

In the accompanying drawing, wherein is shown the preferred, but obviously not necessarily, the only form of embodiment of the invention, Fig. 1 is a side elevation partly in section of an incandescent lamp bulb of standard commercial type to which the present invention has been applied. Fig. 2 is an enlarged detail view illustrating the application of the thermostatic flasher to a standard commercial lamp bulb. Fig. 3 is a detail perspective view of the thermostatic flasher switch removed from the mount. Fig. 4 is a detail sectional view of a modification wherein the flasher switch is hermetically sealed 15 within the chamber of the bulb mount. Fig. 5 is a detail sectional view of a further modification wherein the flasher switch is mounted directly upon the wall of the mount or stem within the bulb. Fig. 6 illustrates a further modification 20 showing the mounting of a resistance element or automatic rheostat within the mount in lieu of the thermostatic switch.

Like parts are indicated by similar characters of reference throughout the several views.

25 While the present invention is directed primarily to the incorporation of an automatic flasher element as a unitary part of an incandescent lamp, it will be understood that the means and method herein shown and described 30 may be employed to incorporate in an incan-

descent lamp or in a radio tube, or the like, an automatic rheostat or resistance element, or any other filament regulating or control member.

Referring to the accompanying drawing, 1 is the bulb of a standard commercial type incandescent lamp, 2 is the screw base for attachment to the socket or lighting fixture. Such lamp bulb 1 is formed with an inwardly projecting hollow or tubular mount 3, the lower end of which, during the process of lamp manufacture is flared 10 outwardly at 4 and united with the marginal walls of the bulb 1. The inner end of the mount 3 while heated to plastic condition is compressed about the filament leads 5 and 6 which are sealed in such contracted or compressed portion 7, 15 known as the "press". Projecting within the bulb 1 from the press 7 is the standard or support 8 upon which is carried the illuminating filament 9 connected with the circuit leads 5 and 6. Attached interiorly to the hollow mount 3 20 adjacent to its "press" and communicating with the interior of the bulb 1 through the wall of the hollow mount 3 is a tubulating stem or evacuation tube 10. Through this stem or tube 10 the oxygen contents of the bulb 1 is exhausted. 25 If the lamp is of the so-called gas filled type, a charge of inert gas may be admitted through the same tubulation stem 10. After exhausting the bulb 1 to cause a vacuum therein, or after filling the bulb with an inert gas the end of the 30 tubulation stem 10 is sealed. This is the usual construction of a commercial type incandescent lamp and per se, forms no part of the present invention. The present flasher lamp has a wide 35 field of usefulness for decorative purposes as to provide a twinkling lamp for a Christmas tree, and carnival use for which purposes the use in large numbers of separate flasher means in the present lamp circuits is prohibited by their cost. 40 The present lamp may further be employed for general sign and signal purposes.

Filament control.—In applying the present invention to a commercial incandescent lamp, as described, the control element, whether it be a thermostatic switch, a rheostat or resistance element, or a safety fuse, such element is located 45 within the compartment or chamber 11 interiorly of the mount 3. In a simple form, as illustrated, a bi-metal thermostatic bar 12 of comparatively small dimensions is secured to a split collar or band 13, preferably having a degree of resiliency or spring action. The spring collar 13 is slidingly adjusted upon the tubulating stem 10 and over one of the filament leads, which in the present instance is the lead 5. In its adjusted position 50

tion the spring band 13 surrounding the supporting stem 10 also encloses the end of the lead 5, which for greater security, and to prevent accidental displacement of the thermostat supporting band 13 is turned upwardly into a hook form exteriorly of the band or collar 13. Ordinarily the clamping action of the collar upon the filament lead will afford sufficient contact. However, to insure a perfect electrical connection the filament lead 5 may be soldered, welded or otherwise integrally united to the collar 13 or directly to the thermostatic bar 12. To make this connection efficiently and economically, a small deposit of solder may be placed upon the spring collar 13 before mounting it upon the tube 10. After being adjusted exteriorly of the tube and the lead 5 a small heated rod or wire may be introduced into the recess 11, and sufficient heat applied to the solder deposit to unite the lead 5 with the collar 13. Located upon the stem 10 in spaced relation with the bar supporting collar 13 is a second collar 14 which carries a contact 15, preferably though not necessarily, or silver, for engagement of the thermal bar 12. Attached to the collar 14 by soldering, welding or otherwise is the continuation 5' of the filament lead. Surrounding the bar 12 is a heater coil 16 of fine wire, one end of which is connected with the bar 12 or with the collar 13, while the other end is connected with the contact supporting collar 14. Thus the heater coil 16 is introduced into the filament lead and permanently connects the portions 5 and 5'. This heater coil is of sufficient resistance that so long as the current passes through the heater coil the filament 9 will not become incandescent, or in any event, will glow but dimly. As the coil 16 heats the thermal bar 12 the latter will be warped or flexed under influence of unequal expansion of its component metals until the free end of the thermal bar 12 engages with the contact 15 upon the supporting collar 14. This will form a shunt bridging the heater coil 16 and connecting the filament lead portions 5 and 5' directly one with the other from the collar 13 to the collar 14 independently of the heater coil. The current thus passing through the thermal bar causes the filament 9 to become incandescent during the period of contact of the bar 12 with the contact 15. During this time the heater coil 16 cools and permits cooling of the thermal bar 12, the reaction of which effects the breaking of the contact between the bar 12 and the contact 15, thereby again bringing the heater coil into the circuit. Current again passing through the heater coil heats the thermal bar 12 and the contact is again re-established. This alternation of make and break between the thermal bar 12 and the contact 15 upon the collar 14 is continued indefinitely, effecting an intermittent flashing of the lamp filament 9.

For ordinary commercial use, for signs and signal purposes, and the like, the thermostatic chamber 11 within the hollow mount 3, is not sealed. It is, however, enclosed and protected by the metallic screw base 2. There may be conditions of use, however, wherein it is desired to operate the thermostatic element 12 within a vacuum or within a body of inert gas, such as neon, helium, or the like. In such case, the tubulating stem 10 is burned off or sealed within the chamber 11 of the mount 3 so that it does not project beyond the base end of the bulb 1, and a sealing disc 17 is applied to the bottom of the bulb 1, and its margins fused thereto after the installation of the thermal control means. The

leads 5 and 6 in such event are brought out of the bulb between the sealing disc 17 and the base margin of the bulb being sealed in the joint while the material is in a plastic condition.

To facilitate the engagement of the lead wires 5 and 5' with the respective collars 13 and 14 these collars are preferably formed with a slight crimp or interiorly grooved bead 18, which will conform to and enclose the end of the lead wire while the remainder of the spring collar will conform closely and tightly to the tubulating stem 10. Obviously, other means of mounting the thermal bar 12 upon the tubulating stem 10 may be employed. In the event that the control element is applied to a bulb that does not include a tubulating stem 10, or if it be desired to mount the element independently of such stem the thermal bar 12 and its cooperating contact 15 may be mounted upon expansible collars or rings 19 engaging the interior walls of the hollow mount 3 under expansive tension as shown in Fig. 5. In Fig. 6 there is shown a modification, where in lieu of the thermostatic bar 12 there is substituted a control element 20 which may be a resistance element or automatic rheostat, or in lieu thereof, such element 20 may comprise a fuse, or other electrical element regulating or controlling the filament 9. As a protection against possible short circuiting of the second filament lead 6 upon the supporting collars 13 or 14 such lead 30 is preferably, though not necessarily insulated in the chamber 11 by slipping over such lead a short length 22 of insulating material of tubular form.

In the event the control element is hermetically sealed within the mount the chamber 11 may be exhausted by fusing of a tube to a disc 17 and blowing a hole through the softened disc before assembly, through which the oxygen may be removed, and if desired, a change of inert gas admitted. The thermal bar 12 is preferably, though not necessarily tapered, whereby it is of less width at its free end. This renders it somewhat more sensitive and facilitates the flexing action.

From the above description it will be apparent that there is thus provided a construction of the character described, possessing the particular features of advantage before enumerated as desirable, but which obviously is susceptible of modification in its form, proportions and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. An incandescent lamp having a hollow filament mount and an evacuation tube extending through the interior of the mount, a thermostatic switch member, a mounting collar therefor slidably carried by the tube, a contact collar for engagement by said switch, also slidably carried by said tube, one of the lamp filament leads being connected with the switch member, a continuing circuit lead connected with the contact collar and interconnected with each other by the circuit closing action of the switch, and a

heater coil also enclosed within said hollow mount and bridged across the thermostatic switch for influencing the action of said switch to effect intermittent flashing operation of the lamp.

5. 2. The combination with an incandescent lamp having a hollow filament mount and an evacuation tube extending therethrough, of a thermostatic circuit switch located within said hollow mount, means for engaging said switch with said 10 tube, a contact member with which the switch operates, means for engaging said contact with said tube in spaced relation with the engagement of said switch, said switch being adapted intermittently to engage said contact to effect a flashing action of the lamp filament.
3. The combination with an incandescent lamp having a tubular mount for the lamp filament through which the lead conductors extend, a tubular stem mounted in and concentric with said 15 mount, of a thermostatic make and break assembly including a fixed contact carried by said stem and a movable contact carried by a thermostatic element mounted upon said stem.
4. As an article of manufacture, a stem assembly including an exhaust tube, and a make and 5 break mechanism coaxially arranged about and carried by said exhaust tube and disposed lengthwise with respect to the tube.
5. The combination with an incandescent lamp having a tubular mount for the lamp filament 10 through which the lead conductors extend, a tubular stem mounted in said mount, of a thermostatic make and break assembly including a movable contact carried by a thermostatic element having one end thereof mounted in fixed relation 15 upon said stem, and a contact arranged in fixed relation with respect to one end of said thermostatic element and located in the path of the movable contact.
